Filed Apr. 16, 1962, Ser. No. 69,723

Term of patent 14 years

(Cl. D33—19)

FIG. 5

FIGURE 1 is a side elevational view of a combined table and beverage cabinet according to my invention, the reverse side being substantially a mirror image thereof but omitting the vertical junction line adjacent to the right side;

FIGURE 2 is a top plan view of the combined table and beverage cabinet shown in FIGURE 1;

FIGURE 3 is an end elevational view of the combined table and beverage cabinet of FIGURES 1 and 2;

FIGURE 4 is an elevational view of the end of the combined table and beverage cabinet opposite the end shown in FIGURE 3; and

FIGURE 5 is an isometric view of the combined table and beverage cabinet in the open position.

I claim:

The ornamental design for a combined table and beverage cabinet, as shown and described.
